UNITED STATES PATENT OFFICE.

ISABELLA M. BIRD, OF STANTON, NEW JERSEY.

NURSING-BOTTLE HOLDER.

SPECIFICATION forming part of Letters Patent No. 651,647, dated June 12, 1900.

Application filed July 14, 1899. Serial No. 723,765. (No model.)

To all whom it may concern:

Be it known that I, ISABELLA M. BIRD, a citizen of the United States, residing at Stanton, in the county of Hunterdon and State of New Jersey, have invented certain new and useful Improvements in Nursing-Bottle Holders; and I do hereby declare the following to be a full, clear, and exact description of the invention, such as will enable others skilled in the art to which it appertains to make and use the same, reference being had to the accompanying drawings, and to letters of reference marked thereon; which form a part of this specification.

15 The objects of this invention are to hold the nursing-bottle with greater security in a convenient position for use by the infant as it lies in its crib or bed, to reduce the cost of the device and enable the bottle to be arranged therein with greater convenience and ease as well as security, and to obtain other advantages and results, some of which may be referred to hereinafter in connection with the description of the working parts.

20 25 The invention consists in the improved nursing-bottle holder and in the arrangements and combinations of parts of the same, all substantially as will be hereinafter set forth, and finally embraced in the clauses of the claim.

30 Referring to the accompanying drawings, in which like letters of reference indicate corresponding parts in each of the views, Figure 1 is a view showing the improved bottle-holder with a nursing-bottle therein attached to a pillow upon which the infant's head may rest. Fig. 2 is a detail plan of the improved bottle-holder. Fig. 3 is a sectional view taken at line *x*, and Fig. 4 is a sectional view taken at line *y*, both section-lines being shown in Fig. 2.

35 40 45 50 In said drawings, *a* indicates a pillow to which the holder may be attached, and *b* indicates the holder, adapted to receive a nursing-bottle *c* and hold the same firmly in position so that the infant may conveniently grasp the nipple *d* and employ the same in the usual way. The said holder *b* comprises a body *e*, of suitable textile fabric or other flexible material and preferably flannel. This is adapted to encircle the body of the bottle and is open at its opposite ends, the end *f* be-

ing small to receive the neck of the bottle, the opening *f'* permitting the out-passage of the said neck, but the walls of said opening 55 preventing the out-passage of the body portion of said bottle.

The opposite end *g* of the body of the bottle-holder is larger, as above indicated, than the end *f*, and the opening *g'* therein is of sufficient size to permit the passage therethrough of the entire body of the bottle. At said larger end the fabric is turned inward, the inward edge being sewed, as at *g*², to form a pocket *g*³ for a shirr string or tape *h*. The said body 60 *e* is preferably formed by laying two similarly-shaped pieces of cloth upon one another and sewing the opposite side edges together, seams *i* being thus formed, which extend from end to end of the body, as shown in Figs. 3 and 4. 70 In sewing one of the seams *i* I inclose between the edges of the body the end of a tongue *j*, comprising a piece of textile fabric, preferably similar to that from which the body is formed. This may be of one or more thicknesses and is sewed in place preferably by the same line of stitching which fastens the edges of the body together. The said tongue *j* extends laterally out from the body *e* and serves as a convenient means for fastening the bottle-holder to the pillow by means of a safety-pin *k*, Fig. 1, or other suitable means. The said parts being constructed as described and the shirr-string being arranged in its pocket 75 *g*³, I first thrust the bottle through the larger opening of the body *e* until the enlargement at the base of the neck of the bottle engages the walls around the smaller opening. I then draw upon the shirr-string *h* and close the larger opening, so that the bottle is held 80 firmly in position and cannot be drawn by the infant from the holder, even though considerable draft be brought to bear upon the nipple connected with the bottle. Thus there is no danger of detachment of the bottle from 85 its said holder, and inasmuch as the inclosing body is of soft material it serves as a cushion to prevent any injury by hard contact of the bottle with the infant. The radiation of heat from the bottle is also retarded by the 90 inclosing holder, so that the contents of the bottle, especially in winter, remains a longer time at a suitably-high temperature to be 95 taken into the stomach of the child.

It will be understood that the bottle-holder is of a length sufficient to project beyond the bottle and permit the shirr-strings to be drawn and the end of the holder to be closed around the bottom end of the bottle to retain said bottle in place.

The material from which the bottle-holder is made is hygienic in that when soiled it can be readily washed.

10 For winter use I prefer to line or pad the interior of the holder to more effectually prevent radiation of heat and maintain the milk at a temperature conducive to a quick digestion.

15 Having thus described the invention, what I claim as new is—

1. The improved nursing-bottle holder herein described, comprising a body *e*, provided with an opening *f'*, for the neck of the bottle 20 to protrude, and said body entirely covering and inclosing the remainder of the bottle, means for inserting and removing the bottle and means for attaching the bottle-inclosing body to a pillow or the like, substantially as 25 set forth.

2. The herein-described nursing-bottle holder, having a body *e*, of soft non-conduct-

ing material adapted to cushion the sides of the bottle and retain its heat, said body having a permanent opening for the neck of the 30 bottle to protrude but entirely inclosing and covering the body of the bottle, and being provided with a suitable opening for inserting the bottle and means for closing said opening, substantially as set forth.

3. A nursing-bottle holder comprising a textile body part *e*, longer than the bottle, and having a small opening *f'*, at one end through which the neck of the bottle may protrude and a large opening *g'*, at the opposite end through which the bottle may be inserted, a draw-string arranged at said larger opening and adapted to close the body together below the bottom of the bottle, and a tongue *j*, which may be pinned to a pillow, 40 substantially as set forth.

In testimony that I claim the foregoing I have hereunto set my hand this 10th day of July, 1899.

ISABELLA M. BIRD.
